UNITED STATES PATENT OFFICE.

KARL E. PEILER, OF WEST HARTFORD, CONNECTICUT, ASSIGNOR TO HARTFORD-EM-
PIRE COMPANY, OF HARTFORD, CONNECTICUT, A CORPORATION OF DELAWARE.

MULTIPLE GLASS FEEDER.

Application filed March 31, 1921, Serial No. 457,299. Renewed March 11, 1924.

This invention relates to a process of and apparatus for obtaining uniform gathers or charges of molten glass from a supply thereof.

8 To perform this process, a plurality of punties or other gathering implements successively move into contact with a mass of molten glass, accumulate gathers therefrom, and move away to a position where the 10 gathers may be further manipulated or presented to mechanism for subsequent treatment.

In some instances, as for example, where the gathers are to be formed into incandescent lamp bulbs, it is desirable to subject them to further treatment, such as marvering, to preliminarily shape them and form a "skin" or "enamel" thereon, and this invention also provides means for accomplishing this result.

It is also an object of this invention to provide a new and improved means for retaining the gathering devices removably in a carrier. This method and a preferred apparatus for carrying it out are illustrated in the accompanying drawings, although various other forms of mechanical arrangements falling within the scope of the appended claims, might be used.

30 Fig. 1 is a plan view partly in section on the line 1—1 of Fig. 2.

Fig. 2 is a vertical longitudinal section on the line 2—2 of Fig. 1.

35 Fig. 3 is a vertical transverse section on the line 3—3 of Fig. 2, showing diagrammatically the relative positions of the gathering implements, during a part of their translatory movement.

40 Fig. 4 is a partial horizontal section on the line 4—4 of Fig. 2, showing the mechanism for intermittently rotating the carrier.

Fig. 5 is a detail sectional view taken on the line 5—5 of Fig. 1, showing one of the chucks for removably holding the gathering 45 implements.

In the embodiment of the invention shown herein, the glass delivering means, comprises a suitable furnace 1 provided with an orifice 2, preferably delivering the glass in a stream and having a plug 3 controlled by hand-wheel 4, to regulate the size and volume of the stream.

A plurality of gathering implements 5, which may be either solid punties or blow-pipes, are so mounted and moved that their

outer ends intercept the flowing stream, remain therein for a suitable period to gather the glass, and then move away to carry the gathers to positions where they may be subjected to further manipulation, or be removed for further treatment.

For this purpose the gathering implements 5 are supported in chucks 7 rotatably mounted in an annular ridge 8 forming the periphery of a carrier 10, the latter being supported by a standard 11 and intermittently rotated by the hollow shaft 12 which carries a ratchet wheel 13 that is actuated by pawl 14. A pin 16 secures this pawl to arm 15 and is engaged by the slotted end of 70 a lever 17, pivoted to pillar 18, and carrying roller 20, held by spring 21 against cam 22 on shaft 24 supported in arm 25.

The cam 22 has one or more drops 33, for advancing the carrier step by step at suitable 75 intervals. While the pawl 14 is making its return stroke a spring pressed detent 34 engages recesses 35 in carrier 10, locking it against rotation.

A worm wheel 26, on shaft 24, is actuated 80 by worm 27 on shaft 28 carried in suitable bearings in base 31, the shaft being rotated in any convenient manner, either by connections with an associated machine, or by a variable speed motor 32 to permit the speed 85 of the machine to be altered according to requirements.

The gathering implements are preferably inclined slightly downward and are rotated upon their longitudinal axes to accumulate 90 and evenly distribute the glass upon the ends of the implements.

For this purpose each chuck 7 has a shaft 36, carried in bearings in ridge 8 of the carrier 10, a bevel gear 37 being keyed to each 95 shaft 36 and driven by the outer set of teeth 38 on ring gear 39. The latter also has internal teeth 40 by which it is driven from idler 41, actuated by pinion 42 on shaft 43, revolvably carried within hollow shaft 12, idler 41 being 100 carried by a pin 44 in a bracket 45 on the carrier. Bevel gear 46 on shaft 43 is driven by bevel gear 47 on shaft 28, to impart a continuous rotation to the gathering irons. Owing to the relative rotary movement of 105 carrier 10 with shaft 12, and the similar movement of ring gear 39, with its teeth 38 engaging bevel gears 37, the continuous rotation of each gathering implement will be slightly retarded or accelerated according 110

2
to the periods of movement or rest of carrier 10, but this does not affect the function of the gathering implements and may be readily minimized by a proper timing and ratio of the gearing.

5 Further treatment of the glass may be accomplished by presenting the implements to a marverer 49 upon which the gathers will be rotated and moved laterally, preliminarily shaping and chilling their outer surfaces. 10 The marverer may be flat, or may have a curved working face according to form of gather desired, and is supported in proper relation to the gathering implements by 15 brackets 50 secured to standard 11. In Fig. 1 the marverer is shown in its proper relation to the furnace, and in Fig. 2 it is shown diagrammatically at the left of the figure to illustrate its cooperation with the implements. 20

In Fig. 3 the translatory movements of the implements immediately preceding, during and after gathering are shown diagrammatically. The implement just entering the 25 gathering chamber is moved laterally into contact with the downwardly flowing stream. The lateral movement is arrested in that position, but since the gathering implement is continuously rotated the glass forming the 30 lower portion of the stream is wound around or gathered upon the implement as shown in position I. Having obtained the proper size gather, the implement is moved laterally to position II, carrying with it the lower 35 to end of the stream, which then sags down into contact with the next implement to which it adheres and is wound thereon. The winding action separates the cord of glass connecting the implements, and the resultant 40 stub ends, not being chilled by contact with metallic severing devices, are wound upon and absorbed into their respective gathers.

When each implement reaches position III, or another subsequent position of rest 45 in its translatory movement, it may be withdrawn from its chuck, in which it is removably held by the pin 51 pressed by the spring 54 into one or more sockets 53 in the circumferential groove 52, whereupon the implement 50 with its gather may be presented to other mechanism for further treatment.

Where marvering is desired the gathering implements are not removed at position III but continue their translatory and rotating motion until the gathers contact with the marverer for a suitable period, as shown in position IV, V, VI and VII, the removal occurring at a position indicated at VIII or thereafter. Empty gathering implements 60 may be inserted at any convenient position in the cycle before the chucks reach chamber 55. The grooves 52 in the implements enable them to be reinserted at any rotary position of the chucks, and at once retained by the pin 51 entering the groove 52.

This will ordinarily be sufficient to rotate the implement with the chuck. If the implement stops rotating as for example when it reaches the marvering plate, the pin 51 will drop into a socket 53 and drive it positively.

Owing to the peculiar properties of molten glass, it may be desirable to deliver and gather the glass in a chamber the temperature of which may be regulated to maintain 75 the glass in proper working condition. 55 designates such a chamber, which has a bottom orifice 56 in line with and somewhat larger than orifice 2, to permit the glass to flow through it when the apparatus is out 80 of operation, the chamber being heated by burners 57 of any well known kind provided with control valves 58. An annular shield 59 may be mounted on the carrier to protect the mechanism from the heat of the gather- 85 ing chamber.

By thus utilizing a flowing stream of glass, or glass delivering means, the operation of which may be regulated, in connection with a gathering mechanism that may be caused to travel faster or slower, the size and volume of the gathers obtained can be accurately determined and varied. Furthermore, by this process and apparatus successive gathers of uniform size and plasticity 95 are obtained, which may subsequently be formed into finished ware free from scars and chill marks.

I claim as my invention:—

1. The method of feeding molten glass 100 which comprises flowing the glass out of a container in an unsupported stream into a heated chamber, and winding the stream successively on a series of punties which are moved into and out of the chamber.

2. The method of feeding molten glass which comprises flowing the glass into a heated chamber and flowing it onto a series of punties on which it is successively wound as they are moved into and out of the chamber. 110

3. The method of feeding molten glass which comprises flowing the glass into a heated chamber without contacting with the walls thereof, winding it successively upon a series of punties to form a series of gathers and successively moving the punties and their gathers out of the heated chamber.

4. The process of obtaining gathers of glass which consists in moving a gathering implement into and out of contact with an unsupported flowing stream of glass, winding the stream upon the implement to form a gather thereon, and then marvering the gather so obtained. 12

5. The method of feeding molten glass which consists in causing a succession of gathering implements to approach a freely flowing stream of molten glass, winding the stream in turn upon each of the implements 13

- to form gathers thereon, moving the gathers away from the stream of molten glass, and then successively subjecting these gathers to a marvering operation to preliminarily 5 shape them.
6. In an apparatus for feeding molten glass, the combination of a container having a discharge orifice for delivering glass in a flowing stream, a chamber surrounding the 10 orifice for maintaining a heated atmosphere around the stream, a plurality of gathering implements, and means for successively carrying the implements into and out of the chamber to obtain gathers of molten glass 15 from the flowing stream by adhesive contact.
7. In an apparatus for feeding molten glass, the combination of a container having a discharge orifice for delivering glass in a flowing stream, a chamber surrounding the 20 orifice for maintaining a heated atmosphere around the stream, a plurality of gathering implements, means for successively carrying the implements into and out of the chamber and rotating them therein to 25 obtain gathers of molten glass from the flowing stream, and means for intermittently stopping the translatory motion of the gathering implements while each implement is gathering.
8. In apparatus for feeding molten glass, the combination of a container having a discharge orifice for delivering glass in a flowing stream, a chamber surrounding the orifice for maintaining a heated atmosphere 30 around the stream, a plurality of gathering implements, means for imparting rotary motion to the implements, and means for successively carrying the latter into and out of the chamber to obtain successive gathers of 35 molten glass from the stream while rotating in contact therewith.
9. In apparatus for feeding molten glass, the combination of a container having a discharge orifice for delivering glass in a flowing stream, a chamber surrounding the orifice for maintaining a heated atmosphere 40 around the stream, a plurality of gathering implements, means for successively carrying the implements into and out of the chamber to obtain gathers of molten glass from the stream, and means for protecting the implement carrying means from the heat of the chamber.
10. In apparatus for feeding molten glass, the combination of a carrier, a series of gathering implements mounted thereon, means for causing the implements to obtain gathers from a flowing stream of molten glass, a marvering device disposed adjacent the pathway of the implements, and means for successively presenting the implements and their gathers to the marvering device to preliminarily shape the gathers.
11. In apparatus for feeding molten glass, the combination of a carrier, a series of ro-
- tating gathering implements mounted thereon in substantially radial relation, and mechanism for revolving the implements successively into and out of contact with a supply of molten glass to obtain gathers 70 therefrom while preserving the said radial relation.
12. In apparatus for feeding molten glass, the combination of a revolving carrier, a series of chucks rotatably mounted on the carrier, a gatherer mounted in each chuck for successive presentation to a supply of molten glass to obtain gathers therefrom, and resilient means for removably retaining each gatherer in place.
13. In glass gathering apparatus, the combination of a carrier, a chuck carried thereby, a gathering implement carried by the chuck, and resilient means associated with the chuck and the said implement for removably retaining the implement in the chuck longitudinally independently of the rotary position of the chuck when the implement is inserted.
14. In glass gathering apparatus, the combination of a carrier, a chuck rotatably mounted therein, a gathering implement mounted in the chuck, and resilient means associated with the chuck and the said implement for maintaining the implement in longitudinal and rotary relation with the chuck, independently of their rotary relation when the implement is inserted.
15. In a machine for preparing glass blanks for blowing, the combination of a forming plate, and means for simultaneously moving a plurality of gathers progressively upon said plate to shape them and chill their surfaces.
16. In a machine for preparing glass blanks for blowing, the combination of an arc-shaped forming plate, and means for simultaneously moving a plurality of gathers progressively upon said plate to marver them.
17. In a machine for preparing glass blanks for blowing, the combination of an arc-shaped forming plate, and means for simultaneously moving a plurality of gathers progressively upon said plate and for rotating them upon their longitudinal axes as they are moved upon the plate.
18. In a machine for preparing glass blanks for blowing, the combination of a plate for marvering gathers, a rotary carrier provided with a plurality of blow pipes, and means for rotating said carrier to cause gathers at the outer ends of the blow pipes to be simultaneously moved upon and marvered by said plate.
19. In a machine for preparing glass blanks for blowing, the combination of an arc-shaped marvering plate, a rotary carrier provided with a plurality of blow pipes, means for rotating said carrier to cause a

4
plurality of gathers at the outer ends of said blow pipes to be simultaneously moved progressively upon said plate to marver them.

5 20. In a machine for preparing glass blanks for blowing, the combination of an arc-shaped forming plate, a rotatable carrier provided with a plurality of rotatable chucks for detachably receiving the inner ends of

blow pipes, and means for rotating said carrier to cause gathers at the outer ends of blow pipes borne by said chucks to be simultaneously moved upon and marvered by said plate.

Signed at Hartford, Conn., this 28th day 15
of March, 1921.

KARL E. PEILER.
